UNITED STATES PATENT OFFICE.

CHARLES A. BAECHTOLD, OF WESTFIELD, NEW JERSEY, ASSIGNOR TO
LIDGERWOOD MANUFACTURING COMPANY, A CORPORATION OF NEW
YORK.

DERRICK-SWINGING MECHANISM.

SPECIFICATION forming part of Letters Patent No. 749,352, dated January 12, 1904.

Application filed January 31, 1901. Serial No. 45,402. (No model.)

To all whom it may concern:

Be it known that I, CHARLES A. BAECHTOLD, a citizen of the United States, and a resident of Westfield, in the county of Union and State 5 of New Jersey, have invented a new and Improved Derrick - Swinging Mechanism, of which the following is a full, clear, and exact description.

My invention relates to an improvement in 10 devices particularly designed for use in swinging a derrick, and comprises certain novel mechanisms by which a drum may be made to reverse its direction while receiving its power from a shaft revolving in a constant direction.

15 My invention further comprises the combination of the various parts of the engine and the derrick with said drum and its reversing mechanism.

Reference is to be had to the accompanying 20 drawings, forming a part of this specification, in which similar characters of reference indicate corresponding parts in all the figures.

Figure 1 is a plan view of my device connected with an engine. Fig. 2 is an end elevation of the same. Fig. 3 is a longitudinal section of the drum-reversing mechanism, taken upon the line 3 3 of Fig. 4. Fig. 4 is a cross-section taken upon the plane which 25 includes the journals of the bevel-pinions, and Fig. 5 shows the combined winch-head and pinion.

My device is primarily intended as an attachment to hoisting-engines and to be used for the reception of a rope or cable which leads 30 to opposite sides of a bull-wheel placed upon the mast of a derrick, whereby the derrick may be swung into any desired position.

It is evident that the device may be used 35 for other purposes than swinging derricks and also may be built as a component part of the engine, and I do not, therefore, wish to be understood as limiting myself to the use of the device for this particular purpose nor to the device when built as an attachment.

40 In the drawings, A represents a drum of any type of hoisting-engine. The shaft A' of this drum, which is usually non-reversible, is provided with an additional pinion a, which

meshes with a gear B, mounted upon the shaft C of my device. A form of construction 50 which is much preferred by me is partially shown in Fig. 1 and a detail thereof shown in Fig. 5. The pinion or gear a is therein made as a part of the winch-head a'. The shaft C is supported in suitable bearings in the frame 55 C' and is rotated constantly in one direction by means of the connection through the gears a and B with the shaft A' of the hoisting-engine. I have shown this power connection as with one of the drum-shafts. It will, however, be 60 understood that the connection may be made with any convenient portion of the hoisting-engine.

Upon the shaft C is loosely mounted a drum D, upon one end of which is formed a bevel 65 gear-wheel d. Mounted upon this shaft and facing said bevel-gear is a friction-disk E, which is splined to the shaft so that it will turn therewith, but may slide lengthwise thereof. This disk is provided with friction-blocks 70 e, which enter a groove f in a loosely-mounted friction member or disk F, which lies between the friction-disk E and the end of the drum. The outer surface of this friction-disk receives a brake-band G or is otherwise engaged by any 75 suitable brake mechanism, so that the rotation of the disk F may be prevented when desired. The friction-disk has a flange F' projecting toward the drum and preferably terminating closely adjacent to the radial flange d' of the 80 drum, so as to close the space lying between the body of the friction-disk F and the adjacent end of the drum. A cup-shaped member is thus formed.

A bevel-gear H, corresponding in size with 85 the bevel-gear d of the drum, is fixedly secured to the shaft C next to the friction-disk F and between the same and the end of the drum. A spider or frame I is loosely mounted upon the shaft between the bevel-gear H 90 and the end of the drum and preferably snugly filling the space between the same. This spider or frame has its periphery secured to suitable bearing-surfaces upon the cup-shaped friction-disk F by means of bolts i or other suitable 95 means, so that when the two are secured to

gether they form substantially one member. This spider has openings I' opposite each other and adapted to receive the bevel-pinions J . Said pinions are mounted upon pins or journals K , which have their inner ends screwed or otherwise secured into the hub of the spider I . Locking set-screws k^2 are also shown. The spider or frame I , together with the friction-disk F , thus constitute a pinion-carrier, which is provided with friction-surfaces engaging, respectively, with the friction member e and the brake G . These pinions mesh with both of the bevel-gears H and d . Oil-chambers k are provided in these pins or journals, extending lengthwise the axis thereof and reaching to the shaft C . Radial oil-openings k' are provided, reaching to the bearing-surface of the pinions J thereof. The axial hole extends to the outer end of the pin and is closed by means of a screw L , which is threaded in an opening in the flange F' , which lies in line with the axis of said pin or journal. By removing one of these bolts the pinion-journal, as well as the bearing of the spider upon the shaft, may be oiled, and the oiling-opening may then be closed by the insertion of the bolt. Any suitable means are provided by which the friction-disk E may be moved, so as to be engaged or disengaged from the friction-disk F . A spring M of customary form is provided for pushing said disks out of contact.

The reversal of the drum is secured by the means described in the following manner: If the brake G be loosened upon the disk F and the friction-disk E be forced into engagement with the disk F , then the disk F is forced to revolve with the disk E —that is, with the shaft C . This carries the spider I and the pinions J carried thereby around the shaft at the same speed. Consequently as they engage with the bevel-gear H , which is secured to and rotates with the shaft, there is no rotation of the pinions upon their journals and they simply have a motion of translation about the shaft A and serve merely as levers connecting the bevel-gears H and d . Consequently the drum D is made to rotate with the shaft and at the same speed. If, however, it is desired to reverse the direction of the drum, this is done by freeing the friction-disks E and F and by applying the brake to the disk F , so as to prevent or check its rotation. When this occurs, the spider carrying the pinions is either held stationary or is permitted to rotate with the shaft at a less speed. Consequently there will be a rotation of the pinions J upon their shafts, and this motion will be communicated to the drum D , causing the same to rotate upon the shaft and in the opposite direction therefrom. The speed of rotation of the drum D may be made to vary from nothing to the same speed as the shaft in either direction by either setting the fric-

tion devices up hard or by applying them lightly, so as to permit slipping of the parts.

The mechanism herein shown for operating the friction-disk E is of the old and well-known construction, which employs a pin N , movable within a slot extending lengthwise the shaft, and the pin-actuating rod N' , which lies within an axial bore in the shaft and at its outer end passes through a yoke N^2 , with which it is threaded, so that by means of rotation of the rod N' the friction-disk E may be pressed against the disk F . To the outer end of the rod N' is secured the arm or lever O . This being an old and well-known construction which is most frequently employed for such purpose, fuller description and illustration are unnecessary. Any other friction-applying device may be substituted therefor.

Alongside of and parallel with the axis of the drum is placed a shaft P , to which an operating-lever P' is connected. This shaft has two arms p and p' , to the first one of which the friction-operating arm O is connected by means of a link O' and to the other of which the brake-band G is connected. These parts are so arranged that the friction is applied by movement of the lever in one direction, while the brake is applied by the movement of the lever in the opposite direction, while in the central position of the lever neither brake nor friction are in use.

It will be seen that my device is very compact and simple in its construction and may be operated to swing the derrick or to reverse the action of whatever mechanism the cable leading from the drum is connected with by the simple operation of throwing a lever in one direction or the other from its central position.

The device when mounted upon an independent frame may be attached to any form of engine. Whether mounted in this manner or built into the engine-frame, it provides a reversible drum in connection with a non-reversing engine. The rope used with the drum D is placed thereon so as to wind upon one end and to wind off of the other. If desired, the drum may be shortened and made as a winch, so that only a few turns will be needed upon the drum at one time.

The device is well adapted for all uses where a reversible drum is desired in connection with a non-reversing engine.

Having thus fully described my invention, I claim as new and desire to secure by Letters Patent—

1. In combination, a shaft, a member provided with a cogged surface, a member provided with a friction-surface one of said members being revolubly fixed and the other revolubly loose upon said shaft, means whereby one of said members may be moved toward the other, a pinion-carrier provided with two pinion-bearings revolubly loose upon said

shaft between said members, a gear-wheel revolubly fixed to said shaft between said members, a pinion journaled in said pinion-carrier and intermeshing with said cogs and said gear-wheel, and a brake; said pinion-carrier being provided with friction-surfaces engaging, respectively, with said friction member and said brake.

2. The combination with a shaft, a friction-disk mounted to turn with and slide upon the shaft, a drum mounted to turn upon the shaft and held against endwise movement thereon, and a bevel-gear carried by the end of the drum toward said friction-disk, of a cup or hood-shaped friction-disk loosely mounted on the shaft between the first friction-disk and the drum, a bevel-gear secured to the shaft within the hood of said friction-disk, a spider secured within said hood, bevel-pinions journaled in said spider and meshing with the bevel-gears which are respectively fixed to the shaft and carried by the drum, means for engaging the two friction-disks, and a friction-brake adapted to act on the loose friction-disk to hold it against rotation.

3. The combination with a shaft, a cup or hood shaped member and a drum both loosely mounted on the shaft, the drum having a bevel-gear carried by the end next the said hood, of a bevel-gear secured to the shaft between the drum and said hooded member, a spider secured to the hood and between the two bevel-gears, bevel-pinions carried by said spider and meshing with the bevel-gears, and means for frictionally connecting the hooded member with the shaft or to hold it stationary as desired.

4. The combination with a shaft, a cup or hood shaped member and a drum both loosely mounted on the shaft, the drum having a bevel-gear carried by the end next the said hood, of a bevel-gear secured to the shaft between the drum and said hooded member, a spider having a rotative bearing upon the shaft between the two bevel-gears and secured to the inner surface of the hood, bevel-pinions carried by said spider and meshing with the bevel-gears, and means for frictionally connecting the hooded member with the shaft or to hold it stationary as desired.

5. The combination with a shaft, a friction member mounted to turn with the shaft, a co-operating friction member mounted loosely upon the shaft and having a hood or projecting flange on one side, and a drum loose upon the shaft and closing the open end of said hood, of a bevel-gear fixed to the shaft and within the hood, a corresponding bevel-gear carried by the adjacent end of the drum, a spider having a bearing upon the shaft between the two bevel-gears and secured to the hood, bevel-pinions journaled in said spider and meshing with both bevel-gears, the journals of said pinions having longitudinal oil-passages and

the hood having openings registering therewith, plugs closing the said openings in the hood and the outer ends of the oil-passages in the pinion-journals, and means for holding the hooded friction member against turning or to turn with the shaft at will.

6. In combination, a shaft, a member provided with a cog-surface, a member provided with a friction-surface one of said members being revolubly fixed and the other revolubly loose upon said shaft, means whereby one of said members may be moved toward the other, a gear-wheel and a pinion-carrier between said members and respectively revolubly fixed and revolubly loose on said shaft, a pinion journaled in said pinion-carrier and intermeshing with said cogs and said gear-wheel, and a brake; said pinion-carrier being provided with friction-surfaces engaging respectively with said friction member and said brake and the journal of said pinion being provided with a lubricating-passage extending inward to said shaft.

7. The combination with a non-reversible shaft of a hoisting-engine, a combined winch-head and gear secured thereon, an auxiliary shaft having a gear secured thereto and meshing with a first gear, a drum loose upon said auxiliary shaft, a driving member fixed to the shaft, a loose or floating member surrounding the shaft and carrying driving connections between the driving member and the drum, and two friction members, one stationary and the other rotating with the shaft, adapted to engage said floating member.

8. The combination with a non-reversible shaft of a hoisting-engine, a combined winch-head and gear secured thereon, of an auxiliary shaft having a gear secured thereto and meshing with the first gear, a drum loose upon said auxiliary shaft, a driving member fixed to the shaft, a loose or floating member surrounding the shaft and carrying driving connections between the driving member and the drum, and two friction members, one stationary and the other rotating with the shaft, adapted to engage said floating member, a single lever connected with both of said friction members and operating them respectively by swinging to opposite sides of its central position.

9. In a derrick-operating mechanism, in combination, a hoisting-drum, a shaft from which the same is operated, an auxiliary shaft, an operative connection between said shafts, a drum loosely mounted on said auxiliary shaft, a clutch revolubly fixed to said shaft whereby said drum is driven in the same direction with said shaft, a brake and drum-reversing mechanism controlled by said brake whereby said drum may be driven against said shaft.

10. A derrick-swinging attachment for hoisting-engines comprising an auxiliary shaft,

means for connecting it with the engine for rotation in one direction, a drum mounted loosely on said shaft, two friction devices, of which two of the friction members are connected to turn together, the other part of one friction device being connected to turn with the shaft, and the other member of the other friction device having a non-rotative support,

and a rotative driving member connecting drum and shaft and supported to be carried about the shaft by the member having the two friction parts thereon.

CHARLES A. BAECHTOLD.
